[57] CLAIM

The ornamental design for a utility light, as shown and described.

DESCRIPTION

FIG. 1 is a perspective view of a utility light illustrating our new design.

FIG. 2 is a front elevational view of the utility light of FIG. 1 on an enlarged scale.

FIG. 3 is a vertical side elevational view of a first side of a utility light illustrating our new design on an enlarged scale.

FIG. 4 is a vertical side elevational view of the other side of a utility light illustrating our new design on an enlarged scale.

FIG. 5 is a rear elevational view of the utility light of FIG. 1 on an enlarged scale.

FIG. 6 is a bottom plan view of the utility light as in FIG. 1 on an enlarged scale.

FIG. 7 is a top plan view of the utility light of FIG. 1 on an enlarged scale.
